UNITED STATES PATENT OFFICE.

FRED E. BRADFIELD, OF DAVENPORT, IOWA.

DESIGN FOR A REAR-END PORTION OF AN AUTOMOBILE-BODY.

56,219.

Specification for Design.

Patented Aug. 31, 1920.

Application filed November 20, 1919. Serial No. 339,440. Term of patent 7 years.

To all whom it may concern:

Be it known that I, FRED E. BRADFIELD, a citizen of the United States, residing at Davenport, in the county of Scott and State of Iowa, have invented a new, original, and ornamental Design for Rear-End Portions of Automobile-Bodies, of which the following is a specification, reference being had to the accompanying drawings, forming part thereof.

In the drawings,—

Figure 1 is a perspective view of the rear end portion of the body of a roadster automobile showing my new design.

Fig. 2 is a side view of the part shown in Fig. 1.

Fig. 3 is a rear view of the same.

I claim:

The ornamental design for a rear end portion of an automobile body, as shown.

FRED E. BRADFIELD.
